(57)

CLAIM

The ornamental design for a laboratory apparatus for non contact liquid handling tasks, as shown and described.

DESCRIPTION

1. Laboratory apparatus for non contact liquid handling tasks

1.1 : Front
1.2: Right
1.3: Back
1.4: Left
1.5: Top
1.6: Bottom
1.7 : Perspective

The broken lines depict portions of the laboratory apparatus for non contact liquid handling tasks that form no part of the claim.

1 Claim, 7 Drawing Sheets
